UNITED STATES PATENT OFFICE.

EMIL STRANSKY, OF NEW YORK, N. Y.

FUSE-CARTRIDGE.

1,151,135.

Specification of Letters Patent. Patented Aug. 24, 1915.

Application filed November 21, 1914. Serial No. 873,875.

To all whom it may concern:

Be it known that I, EMIL STRANSKY, a subject of the Emperor of Austria-Hungary, residing at New York, in the county of New York and State of New York, have invented new and useful Improvements in Fuse-Cartridges, of which the following is a specification.

This invention relates to improvements in fuse cartridges and has particular application to a multiple fuse cartridge.

In carrying out the present invention, it is my purpose to provide a multiple fuse cartridge which may be readily and conveniently slipped into the usual cartridge jaws connected in an electric circuit and wherein the body of the cartridge may be revolved while connected to the jaws so that a new fusible element may be connected in the circuit in the event of the original fusible element being burnt out.

It is also my purpose to improve and simplify the general construction of multiple fuse cartridges and to provide a cartridge which may be manufactured and marketed at comparatively small cost, and which may be applied to the cartridge holding jaws in an electric circuit and removed from such jaws with ease and facility.

With the above and other objects in view, the invention consists in the construction, combination and arrangement of parts hereinafter set forth in and falling within the scope of the claims.

In the accompanying drawing; Figure 1, is a view in side elevation of a multiple fuse cartridge constructed in accordance with the present invention. Fig. 2 is a longitudinal sectional view therethrough. Fig. 3 is a cross sectional view on the line 3—3 of Fig. 2. Fig. 4 is a similar view on the line 4—4 of Fig. 2. Fig. 5 is a cross sectional view on the line 5—5 of Fig. 2. Fig. 6 is a like view on the line 6—6 of Fig. 2.

Referring now to the drawing in detail, 1 designates the body of the cartridge. In the present instance, this body is circular in cross section and has the opposite extremities thereof circumferentially reduced as at

2, 3, the body being formed of porcelain, fiber or other material having insulating properties. Formed in the body 1 and extending longitudinally thereof are passages 4 spaced apart equidistant and arranged in a circular row about the longitudinal axis of 55 the body. Disposed within the extremities of the respective passages 4 at the end 2 of the body are pins 5 suitably secured within the passages and having the outer ends thereof formed with heads 6 lying against 60 the end of the body, while disposed within the remaining end portions of the respective passages 4 are fingers 7 having the outer ends thereof disposed upon the end edge of the end portion 3 of the body. Within 65 the passages 4 are fusible elements 9 respectively and the extremities of each fusible element are suitably fastened to the inner ends of the axially alining pin 5 and finger 7 in the end portions of the particular passage 70 4.

In the present instance, the body 1 is formed centrally with a longitudinally extending bore 10 through which is passed a core 11 formed of porcelain or other suitable 75 insulating material and secured to the end of the core 11 beyond the end portion 2 of the body is a head 12 having the inner surface thereof in face to face contact with the adjacent end edge of the body. The head 12 is preferably of a diameter substantially equal to the diameter of the adjacent end portion of the body and formed in the head 12 and adapted to aline axially with any one of the passages 4 in the body is a passage 80 13 having the inner end thereof diametrically enlarged as at 14 to receive the head 6 of the pin in the particular alining passage.

Disposed within the passage 13 is a current conducting pin 15 having the inner end thereof formed with a head 16 disposed within the diametrically enlarged portion 14 of the passage 13 and designed to engage the adjacent head 6. Inclosing the head 12 and the adjacent end portion 2 of the body 1 is a cap 17 having the end wall suitably secured to the outer end of the pin 15 and

the inner end portion 2 of the flange or side wall thereof loosely surrounding the circumferentially reduced portion 2 of the body so that the latter may be freely revolved about the core 11 relatively to the head 12 and cap 17.

5 The remaining end portion of the core 11 projects beyond the end edge of the end portion 3 of the body and secured to such 10 projecting end portion of the core is a head 18 having the inner face thereof confronting the adjacent end of the body and spaced apart therefrom, the head 18 being of a diameter substantially equal to that of the 15 reduced portion of the body.

Disposed upon the end edge of the end portion 3 of the body is a metal disk 19, while surrounding the outer end of the core 11 adjacent to the inner surface of the head 20 18 is a metal disk 20 and interposed between the confronting faces of the disks 19 and 20 is a coiled expansion spring 21. In the present instance, the fingers 7 are stamped from the metal of the disk 19.

25 Formed on the periphery of the disk 19 and overlying the circular wall of the end portion 3 of the body are metal fingers 22, while formed on the periphery of the disk 20 and overlying the fingers 22 is a metal sleeve 30 23. These fingers 22 are preferably of springy material so as to effectively engage the sleeve 23.

Inclosing the head 18, sleeve 23 and surrounding the reduced portion 3 of the body 35 1 is a cap 24 having the side wall thereof connected with the metal sleeve 23 by means of set screws 25. The sleeve 23 and the side wall of the cap 24 loosely surround the adjacent end portion of the body 1 and as the 40 side wall of the cap 17 also loosely surrounds the end portion 2 of the body 1, the body 1 may be revolved around the core 11 relatively to the caps and heads 12 and 13.

In practice, the side walls of the caps 17 45 and 24 are set into the respective jaws or clips connected in an electric circuit and the current flows from the cap 17 through the pin 15 and head 16, the head 6 in engagement with the head 16, the pin 5 of said head 6, the fusible element 4, the finger 7 connected to such fusible element, the plate or disk 19, spring 21, disk 20, metal sleeve 23, and the side wall of the cap 24. The metal fingers 22 on the periphery of the disk 19 in engagement with the sleeve 23 insure the proper flowing of the current irrespective of the spring 21.

When the particular fuse wire connected in the circuit burns out, the body 1 is revolved around the core 11 relatively to the caps 17 and 24 and in the rotation of the body 1 the head 6 of the pin 5 within the diametrically enlarged end portion 14 of the passage 13 rides out of such passage against the action of the spring 21, and the next

adjacent head 6 drops into the enlarged portion of the passage 13 when such head registers with the passage, thereby placing a new fusible element in the circuit.

It will be noted that the spring 21 performs the dual function of a conductor and holding device whereby the body 1 is held stationary when the head 6 of one of the pins 5 is in engagement with the head 16 on the pin 15.

75 From the foregoing description taken in connection with the accompanying drawing, the construction, mode of operation and manner of employing my improved multiple fuse cartridge will be readily apparent. It 80 will be seen that I have provided a multiple fuse cartridge wherein the body of the cartridge carrying the fusible elements may be revolved about its longitudinal axis to place the fusible elements in the circuit successively or one after the other as the same become mutilated, while the body will be maintained stationary as long as the particular fusible element is connected in the circuit, thereby eliminating accidental breaking of the circuit at the fuse. In this instance, the outer end portions of the caps 17 and 24 are non-circular in cross section so that such caps will remain stationary within the jaws of the cartridge holder in the turning 95 of the body 1 of the cartridge.

90 The passages 4 preferably open onto the outer surface of the body 1 so that the fusible elements may be quickly replaced when the same burn out, and the end portions of the passages are closed to the outer surface of the body by means of suitable material.

100 While I have herein shown and described the preferred form of my invention by way of illustration, I wish it to be understood that I do not limit or confine myself to the precise details of construction herein described and delineated, as modification and variation may be made within the scope of the claims without departing from the spirit 110 of the invention.

I claim:

1. A multiple fuse cartridge comprising a core, heads on the opposite ends of said core, a body rotatably mounted on said core between said heads and having one end in face to face contact with one of said heads, an electric current carrying pin carried by the head in contact with the body and adapted to be connected to one side of an electric circuit and having the inner end thereof exposed to the adjacent end of said body, fusible elements carried by said body arranged longitudinally thereof and spaced apart around the body, contact heads on the end of said body in engagement with said head and connected to the adjacent ends of said fusible elements respectively and adapted to engage said current carrying pin successively as the body is rotated, means con-

5 nected with the remaining ends of said fusible elements whereby the latter may be connected to the other side of the electric circuit, and means interposed between the remaining head and the adjacent end of said body and acting upon the latter to hold the particular contact head in engagement with said current carrying pin, said last-named means permitting longitudinal movement of 10 the body along the core to disengage the particular head from said pin.

15 2. A multiple fuse cartridge comprising a core, heads on the opposite ends of said core, a body rotatably mounted on said core between said heads and having one end in face to face contact with one of said heads, an electric current carrying pin carried by the head in contact with the body and adapted to be connected to one side of an electric 20 circuit and having the inner end thereof exposed to the adjacent end of said body, fusible elements carried by said body arranged longitudinally thereof and spaced apart around the body, contact heads on the 25 end of said body in engagement with said head and connected to the adjacent ends of said fusible elements respectively and adapted to engage said current carrying pin successively as the body is rotated, means connected with the remaining ends of said 30 fusible elements whereby the latter may be connected to the other side of the electric circuit, and a spring surrounding said core between the remaining cap and the adjacent 35 end of the body and acting upon the latter to hold the particular contact head in engagement with said current carrying pin, said spring permitting the body to move longitudinally along the core to disengage said 40 head from said pin.

45 3. A multiple fuse cartridge comprising a core, heads on the opposite ends of said core, a body rotatably mounted on said core between said heads and having one end in face to face contact with one of said heads, an electric current carrying pin carried by the head in contact with the body and adapted to be connected to one side of an electric 50 circuit and having the inner end thereof exposed to the adjacent end of said body, fusible elements carried by said body arranged longitudinally thereof and spaced apart around the body, contact heads on the 55 end of said body in engagement with said head and connected to the adjacent ends of said fusible elements respectively and adapted to engage said current carrying pin successively as the body is rotated, means connected with the remaining ends of said 60 fusible elements whereby the latter may be connected to the other side of the electric circuit, means interposed between the remaining head and the adjacent end of said body and acting upon the latter to hold the 65 particular contact head in engagement with

said current carrying pin, said last-named means permitting longitudinal movement of the body along the core to disengage the particular head from said pin, and caps carried by said heads respectively and inclosing the ends of said body. 70

75 4. A multiple fuse cartridge comprising a core, heads on the opposite ends of said core, a body rotatably mounted on said core between said heads and having one end in face to face contact with one of said heads, an electric current carrying pin carried by the head in contact with the body and adapted to be connected to one side of an electric circuit and having the inner end thereof exposed to the adjacent end of said body, fusible elements carried by said body arranged longitudinally thereof and spaced apart around the body, contact heads on the end of said body in engagement with said head and connected to the adjacent ends of said fusible elements respectively and adapted to engage said current carrying pin successively as the body is rotated, a metal disk disposed concentrically of said core and in engagement with the remaining end of said body, fingers formed integral with said disk and connected with the remaining ends of said fusible elements respectively, a second set of fingers formed on said disk and disposed upon the outer side of the adjacent end portion of the body and adapted to be connected to the other side of the electric circuit, and means interposed between the remaining head and the adjacent end portion of said body and acting to hold the particular contact head in engagement with said current carrying pin. 85 90 95 100

105 5. A multiple fuse cartridge comprising a core, heads on the opposite ends of said core, a body rotatably mounted on said core between said heads and having one end in face to face contact with one of said heads, an electric current carrying pin carried by the head in contact with the body and adapted to be connected to one side of an electric circuit and having the inner end thereof exposed to the adjacent end of said body, fusible elements carried by said body arranged longitudinally thereof and spaced apart around the body, contact heads on the end of said body in engagement with said head and connected to the adjacent ends of said fusible elements respectively and adapted to engage said current carrying pin successively as the body is rotated, a metal disk disposed concentrically of said core and in engagement with the remaining end of said body, fingers formed integral with said disk and connected with the remaining ends of said fusible elements respectively, a second set of fingers formed on said disk and disposed upon the outer side of the adjacent end portion of the body and adapted to be connected to the other side of the electric 110 115 120 125 130

circuit, means interposed between the remaining head and the adjacent end portion of said body and acting to hold the particular contact head in engagement with said 5 current carrying pin, a cap secured to the pin carrying head and inclosing the latter and the adjacent end portion of the body, and a cap carried by the remaining head and

inclosing said last-mentioned means and the last-named fingers.

In testimony whereof I affix my signature in presence of two witnesses.

EMIL STRANSZKY.
